CONSOLE INSTRUMENT BOARD

Ward J. O'Connor, Bayonne, N. J., assignor to
The Lummus Company, New York, N. Y., a cor-
poration of Delaware

Application May 17, 1950, Serial No. 10,003

Term of patent 7 years

(Cl. D26—5)

To all whom it may concern:

Be it known that I, Ward J. O'Connor, a citizen of the United States, residing at Bayonne, county of Hudson, State of New Jersey, have invented a new, original, and ornamental Design for Console Instrument Board, of which the following is a specification, reference being had to the accompanying drawing, forming a part thereof.

Fig. 1 is a perspective view of an instrument board, showing my new design; and

Fig. 2 is a top plan view of the instrument board, upon a reduced scale.

The back of the article is plain.

I claim:

The ornamental design for a console instru-
ment board, as shown and described.

WARD J. O'CONNOR.
